DESIGN FOR A COIN BANK

Ralph Victor Moran, Bradford, Pa., assignor to
Vic Moran, a partnership composed of Marion
C. Moran, Elizabeth M. Moran, and Vic Moran,
Bradford, Pa.

Application October 30, 1945, Serial No. 123,327

Term of patent 14 years

(Cl. D34—11)

To all whom it may concern:

Be it known that I, Ralph Victor Moran, a citizen of the United States, residing at Bradford, in the county of McKean and Commonwealth of Pennsylvania, have invented a new, original, and ornamental Design for Coin Banks, of which the following is a specification, reference being had to the accompanying drawing, forming part thereof.

In the drawing:

Fig. 1 is a front elevational view of a coin bank, showing my new design;

Fig. 2 is a vertical sectional view taken on the line 2—2 in Fig. 1, looking in the direction of the arrows; and

Fig. 3 is a horizontal sectional view taken on the line 3—3 of Fig. 1, looking in the direction of the arrows.

I claim:

The ornamental design for a coin bank, as shown.

RALPH VICTOR MORAN.
